GRINDING MACHINE

Carl J. Hertlein, Brooklyn, N. Y., assignor of
one-half to Franz Fuchs, Brooklyn, N. Y.

Application October 3, 1936, Serial No. 103,838

25 Claims. (Cl. 51—166)

The invention relates in general to a grinding machine and specifically relates to the tool spindle and to the associated motor drive of such machines; to the mechanism for shifting the grinding tool vertically and to an organization of control stops for limiting the travel of the grinding tool.

The present application constitutes a companion application to an adjustable work bed for supporting the work acted upon by the tool and associated mechanism herein disclosed and which application is entitled "Adjustable work bed", Serial No. 103,839 filed October 3, 1936.

The primary object of the invention is to improve and simplify grinding machines so as to provide among other things for both a coarse adjustment and setting of the grinding tool at an operative working position, as well as a refined micromechanical adjustment of the tool as circumstances may indicate as desirable, particularly in the control and presetting of the limits of movement of the tool in its vertically movable direction during the coarser movements.

The invention has for other objects the providing of easily and quickly manipulated means for controlling the belt tension between the tool spindle and the motor for driving the same; the providing of means for quickly releasing the tension to facilitate shifting of the belt; the providing of stops for limiting the movement of the spindle, which stops can be quickly reset into approximate limiting position and thereafter more accurately set to minutely limit the desired path of travel of the grinding tool.

Various other objects and advantages of the invention will be in part obvious from an inspection of the accompanying drawings and in part will be more fully set forth in the following particular description of one form of grinding machine embodying the invention, and the invention also consists in certain new and novel features of construction and combination of parts hereinafter set forth and claimed.

In the accompanying drawings:

Fig. 1 is a view largely in side elevation and with a small portion at the bottom of the carriage broken away to show the lower plunger stop and illustrating a preferred embodiment of the invention;

Fig. 2 is a view largely in front elevation of the right side of the preceding figure and partly in vertical section taken on the plane indicated by the line 2—2 of Fig. 1;

Fig. 3 is a rear elevational view looking at Fig. 1 from the right side thereof;

Fig. 4 is a view in side elevation showing the side opposite to that shown in Fig. 1 and with the upper portion of the main column broken away to show parts of the micrometer screw feed;

Fig. 5 is a horizontal sectional view somewhat enlarged and taken on the plane indicated by the line 5—5 of Figs. 1 and 4;

Fig. 6 is a detailed vertical sectional view taken on the plane indicated by the line 6—6 of Fig. 5 looking in the direction indicated by the arrow; and

Fig. 7 is a detailed plane view of the stops shown at the top of the carriage in Figs. 1 and 2.

In the drawings there is shown a supporting tank 10 designed to hold the drip water from the tool. Mounted on a bed plate 11 therein are two large uprights, a main column 12 and a fulcrum standard 13. The main column comprises a rugged casting including side plates 14 and 15 connected across their fronts by a face plate 16 provided with forwardly projecting and vertically extending guideways 17 and 18, and merging into a wide spreading base 19. Slidably mounted on the guideways 17 and 18 is a vertically shiftable carriage 20 of greater width than the face plate 16 and side lapping the forward edge portion of the side plates 14 and 15. The carriage is enlarged at its lower portion to form a forwardly extending horizontal extension 21 for supporting the grinding tool and associated parts. The extension 21 is relatively wide as shown in Fig. 2 and has supported thereon a spindle quill 22 in which is rotatably mounted a tool spindle 23 projecting from one end of the quill. A grinding tool 24 is replaceably mounted on the end of the spindle 23 following conventional practices in this respect. The opposite end portion of the spindle is provided with a driven multi-speed spindle pulley 25, the free end of which is journaled in a bearing 26.

The front face of the carriage 20 above the extension 21 is also provided with vertical guide ways 27 in which is slidably mounted the base plate 28 of an electric motor 29. The motor shaft is provided with a spindle pulley 30 in driving relation with pulley 25 by means of a belt 31.

Tension is maintained on the belt by means of a coiled spring 32 positioned between the extension 21 and the underside of the bracket 33 between the motor 29 and the sliding base plate 28 as best shown in Fig. 4. Opposite ends of the spring 32 are maintained in vertical position by a pair of aligned spring guiding fingers 34 and 35, the lower finger 35 being threaded and provided with an adjustable nut 36 forming an ad-

justable bearing for the lower end of the spring. The motor and its associated base plate is limited in its upward movement by the set screw 37 carried by a stop plate 38 at the top of the carriage and with its lower end engaging in a cup 39 formed on top of the motor. The set screw is secured in its vertically adjusted position by means of a binding screw 40.

From this construction it is understood that the tension on the spring 32 is regulated by the manipulation of the nut 36 so as to cause the motor to bear upwardly against the screw 37 which has been preset to give the desired tension on the belt 31.

15 For the purpose of releasing the tension on the belt where it is desired to shift the belt on its pulleys to obtain variation in speed, a plunger 41 is caused to react between carriage and motor to lower the motor against the resistance of the 20 spring 32. The plunger is actuated by a lever 42 pivoted to a bracket 43 carried by the stop plate 38 and to which the plunger is pivoted. The lower end of the plunger is received in a 25 cup-like wear plate 44 similar to the cup 39 and likewise formed integral with the motor base plate 28.

In order to permit the displacement of the motor from the carriage, the stop plate 38 is fulcrumed on a pivot pin 45 and arranged so that 30 its free end 46 (see Fig. 7) normally held in place by a screw 45', may be moved forwardly about the pin 45 and swung out of the path of the base plate 28 and associated parts. In this way the motor can be slid upwardly until clear of the 35 guideways and thus be removed from the carriage.

The carriage and with it the tool spindle and its driving motor may be moved up and down vertically as a single unit by means of a long, 40 forwardly extending, manually-actuated lever 47 provided intermediate its length with a fulcrum nut 48 adjustably mounted in a slot 49 formed in the fulcrum standard 13 and which nut is secured in adjusted position by means of a clamp controlled by a handle 50. The inner end of 45 the lever 47 terminates in a bearing wheel 51 which is in sliding and lifting engagement with a wear plate 52 formed on the underside of the motor bracket 33. The lever is provided at its 50 free end with a handle 53 and secured thereon between the handle and fulcrum is a counter weight 54 designed to balance substantially the weight of the motor carriage and associated vertically movable parts.

55 From this construction it is understood that the fulcrum of the manually actuated lever is adjusted vertically along the standard 13 so as to bring the tool 24 in the region of the work to be ground and with the fulcrum set in place 60 the operator by manipulating the lever may cause the grinding tool to operate bodily in a vertical direction while being rotated by the motor.

For the purpose of providing limits to the permissible vertical movement of the carriage when 65 so actuated grossly by the manipulation of the lever, adjustable stops are provided between the carriage and the main column. For this purpose there is shown in Figs. 1 and 5 a vertically extending channel plate 55 secured to the side plate 70 14. Vertically adjustable on the channel plate are two pairs of adjustable stationary stops numbered downwardly in Fig. 1, 56 to 59. Referring to Fig. 5 it is noted that the stops are each secured in their relatively adjustable position by 75 means of a binding nut 60 within the channel

engaged by a headed screw 61 controlled by lever 62 (see top of Fig. 5). Each stop is provided with an offset 63 threaded through which is a vertical screw 64 secured in its adjusted place by a binding screw 65. In this way the vertical space between adjacent vertical screws of the pair of stops 56 and 57, for instance, may be accurately set first by roughly setting the stops on the main column and then adjusting the vertical screws. Similarly, when it is desired to control the tool 10 travel to the lower portion of the machine, the lower pair of stops 58 and 59 may be utilized and the space between their associated vertical screws may likewise be accurately defined and located. 15

Operating in this space as suggested in Fig. 1 is a carriage stop 66 comprising a plunger 67 urged forwardly by a spring 68. The plunger may be withdrawn into inoperative position against the tension of spring 68 by means of a 20 head 69 particularly shown at the lower portion of Fig. 1. The plunger is provided with a locking pin 70 which, when the plunger is withdrawn may be rotated into position to bear on the adjacent surface 71 of the carriage to hold 25 the carriage stop in its inoperative position. It is herein suggested that a second stop 72 of a similar plunger type be employed above the stop 66 and designed to operate between the upper pair of fixed stops 56 and 57 in those cases where 30 it is desired to operate the grinding tool at relatively higher position off the base of the machine. In the showing in Fig. 1 the plunger of the upper stop 72 is withdrawn and locked in its 35 inoperative position and thus has no control, for the time being, on the possible movement of the carriage.

Considering the showing in Fig. 1 with the lower carriage stop operative and the upper carriage stop inoperative, it is understood that, by lowering the lever handle from its horizontal position shown, the grinding tool may be elevated from its lowermost position, with plunger 67 engaging the top of the lowermost vertical screw into an elevated position for a distance defined by the length 45 of the space between the adjacent ends of the vertical screws forming parts of the stops 58 and 59.

In those cases where a more refined vertical adjustment of the tool spindle and its associated motor is desired, a micrometer lead screw feed 50 may be employed. Such a feed includes a vertically extending lead screw 73 mounted at opposite ends in bearings 74 and 75 formed in the main column. A graduated hand wheel 76 is positioned at the top of the machine and is connected through a worm and gear drive 77 with the lead screw 73 to rotate the same over angles measured on the scale 78. This lead screw is designed to be connected at will with the carriage 60 by means of a split nut 79. The nut is formed of two halves which are mounted in a rectangular casing 80 encircling the lead screw. The two halves of the nut each include an outstanding top flange 81 which overlaps shoulders 82 formed in a pair of end closures 83 of the casing 80 to permit relative movement of the nut halves transversely of the lead screw while holding the nut from movement in all other directions. Opposing springs 84 and 85 bear on the two halves of 70 the split nut and tend normally to force the nut into threaded engagement with the lead screw. The two parts of the split nut are arranged so as to be separated into their inoperative position, spaced from the lead screw by means of a pair 75

of cams 86 positioned between the two halves of the nut and moved to and from operative positions by means of a split nut lever 87 in the form of a U-yoke. The casing is secured in a vertically adjustable position on the carriage by means of a binding screw 88 extending through a vertical slot 89 in the carriage. The screw has a wide head 90 engaging the inner side of the carriage on opposite sides of the slot as more particularly shown in Figs. 5 and 6.

In operation and assuming that the split nut is in its released, inoperative position and that it is desired to operate the grinding tool within the limits defined by the space preset by the adjustment of the stops, hereinbefore described, the manipulation of the long control lever will raise or lower the grinding tool within the preset limits of travel. Should it be desired to work in the upper portion of the available space, for instance, the lower carriage stop is withdrawn into its inoperative position and by re-rotating the plunger controlling the upper stop, it may be caused to project into and thus operate in the space between either the upper or lower pairs of stops.

Should it be desired to set the grinding tool so as to fix or substantially fix in its axis of rotation, the split nut lever is shifted so as to render its associated cams inoperative and thus permit the opposing spring to move the split nut halves into engagement with the lead screw, after which, by the manipulation of the graduated hand wheel at the top of the machine, a refined adjustment in the location of the axis of the grinding tool may be obtained. As this micromechanical adjustment can be obtained at any position within the permissible vertical limits of movement of the tool, it is possible to quickly locate the grinding tool in its approximate desired position by the rough coarse movement provided by the lever and then by moving the split nut organization into engagement with the lead screw at any position where the rough adjustment may have located it, a refined variation in tool positions may be quickly attained.

During the course of operating the machine and wherein it may be desirable to change the speed of rotation of the grinding tool, tension on the belt may be quickly released simply by pulling down on the belt lever, the belt may be shifted conventionally from one to another pair of pulleys, and releasing tension on the plunger permit the elevating spring to restore tension on the belt. Should the belt become too tight or too loose in practice, the adjusting screw at the top of the motor may be unlocked from its previous setting, reset and relocked in its reset position.

By means of a device such as is herein disclosed, extremely refined accuracy in setting the grinding tool and in moving it to and from any preset locations may be obtained quickly, where quick shifting is desired and in moving it over minute and restricted distances may be obtained wherever accurate and refined work is desired.

The stops controlling the vertical adjustment of the tool may be further used as when grinding a number of tools which are similar in that they contain a number of different areas of the same conformation. For instance, the first area may be ground with the plunger 67 limited in its movement in one direction by stop 59. The second area with plunger 72, for instance, is limited in one direction of movement by stop 57; the third area again using plunger 67 and limited in one direction of movement by stop 58 and so on. In general all that is necessary is to engage

the proper plunger with the proper stop to get all of the similarly located areas ground alike. In this way one preset arrangement of the stops permits the identical grinding of any number of tools for which the stops were initially set.

When operating in connection with the work supporting and locating bed plate featured in the companion application above identified, there is provided a precision grinding machine capable of accurately grinding work such as cutting tools of various kinds and which in general is capable of accurately grinding a multiplicity of different contoured surfaces.

While there have been shown, described and pointed out in the annexed claims, certain novel features of the invention, it will be understood that various omissions, substitutions and changes in the form and details of the device illustrated and in its operation may be made by those skilled in the art without departing from the spirit of the invention.

I claim:

1. In a grinding machine, the combination of a base provided with a main column and a fulcrum standard, a carriage slidably mounted for vertical movement on the column, a motor slidably mounted for vertical movement on the carriage, a tool spindle journaled in the lower portion of the carriage beneath the motor for rotary movement about a horizontal axis, a belt driving the spindle from the motor, a spring between the carriage and motor tending to elevate the motor on the carriage, a stop between the motor and carriage for limiting the upward movement of the motor on the carriage, a lever fulcrumed on the standard, having a handle at one end and at the other end engaging beneath the motor to elevate the same together with the carriage on the main column.

2. In a grinding machine, the combination of a base provided with a main column, a carriage slidably mounted for vertical movement on the column, a motor slidably mounted for vertical movement on the carriage, a tool spindle journaled in the carriage beneath the motor for rotary movement about a horizontal axis, a belt driving the spindle from the motor, a spring between the carriage and motor tending to elevate the motor on the carriage, a stop between the motor and carriage for limiting the upward movement of the motor on the carriage, and control means for shifting the assembly including the motor and carriage on the main column thereby to move the tool spindle vertically.

3. In a grinding machine, the combination of a vertically disposed column provided with a guideway, a carriage mounted for sliding movement thereon, a grinding tool spindle rotatably mounted in the carriage, a standard, a lever having its fulcrum adjustably mounted in the standard, said lever being connected at one end to the carriage to move the same vertically in the guideway, having its other end provided with an actuating handle and having a weight carried thereby between the handle and standard and tending to counterweight the carriage and parts carried thereby.

4. In a grinding machine, the combination of a vertically disposed column provided with a guideway, a carriage mounted for sliding movement thereon, a grinding tool spindle rotatably mounted in the carriage, a standard and a manually actuated control lever adjustably fulcrumed to the standard and operatively connected to the carriage to move the tool spindle vertically over

distances controlled by the location of the lever fulcrum.

5. In a grinding machine, the combination of a structural part of the machine, a tool spindle mounted therein for rotary movement, a motor, a belted connection between the motor and spindle, a spring reacting between the motor and structural part for placing tension on the belted connection, and means for regulating the tension 10 placed on the belted connection.

6. In a grinding machine, the combination of a vertically disposed main column provided with a guideway, a carriage slidably mounted for vertical movement on the guideway, a tool spindle 15 journalled in the carriage for rotary movement, an electric motor slidably mounted for vertical movement on the carriage and provided with a multi-speed pulley in belted driving engagement with the spindle in all positions thereof, means 20 for adjusting the location of the motor on the carriage thereby to set it relative to the spindle and manually actuated means engaging the carriage for shifting the spindle and motor when so relatively adjusted, together vertically as a unit 25 and a resilient support between the motor and carriage acting to maintain tension on the belt.

7. In a grinding machine, the combination of a carriage mounted for vertical movement, a grinding spindle mounted for rotary movement in the 30 carriage and provided with a driving pulley, a motor guided for vertical movement on the carriage and provided with a pulley, a belt forming a driving connection between the motor and spindle pulleys, a coiled spring located between the 35 carriage and motor, tending to elevate the motor upwardly away from the spindle and thus place tension on the belt and adjustable means for limiting the elevating movement of the motor under the tension from the spring.

40 8. In a grinding machine, the combination of a carriage mounted for vertical movement, a grinding spindle mounted for rotary movement in the carriage and provided with a driving pulley, a motor guided for vertical movement on the carriage and provided with a pulley, a belt forming a driving connection between the motor and spindle pulleys, a coiled spring located between the carriage and motor, tending to elevate the motor upwardly away from the spindle and thus place 45 tension on the belt and adjustable means for limiting the elevating movement of the motor under the tension from the spring, and manually actuating means for lowering the motor against the tension of said spring to release the tension 50 on the belt and thus permit easy shifting of the belt on its pulleys.

9. In a grinding machine, the combination of a carriage mounted for vertical movement, a grinding spindle mounted for rotary movement in the 60 carriage and provided with a driving pulley, a motor guided for vertical movement on the carriage and provided with a pulley, a belt forming a driving connection between the motor and spindle 65 pulleys, a coiled spring located between the carriage and motor, tending to elevate the motor upwardly away from the spindle and thus place tension on the belt, means for limiting the elevating movement of the motor under the tension from 70 the spring, manually actuating means for lowering the motor against the tension of said spring to release the tension on the belt and thus permit easy shifting of the belt on its pulleys, and manually actuated means for elevating the motor 75 and in causing the motor to bear against said stop

to act therethrough to lift the carriage with its associated tool spindle.

10. In a grinding tool, the combination of a spindle, a spindle quill therefore, a spindle pulley in driving engagement with the spindle, a 5 motor provided with a spindle pulley, a belted connection between the two pulleys and a spring between the quill and motor, tending to support the motor from the quill and reacting between the spindle and motor tending to place the belt 10 under tension, and an adjustable stop for one end of the spring for varying the tension of the spring and thus varying the tension of the belt.

11. In a grinding machine, the combination of a carriage, a spindle quill carried thereby, a 15 spindle rotatably mounted in the quill, a spindle pulley journalled in the carriage and in driving engagement with the spindle, a motor mounted for vertical movement, a motor pulley, a belt connecting the two pulleys, a spring engaging the 20 motor and urging the same upwardly against the tension of the spindle pulley, means for varying the tension of the spring, a stop for limiting the upward movement of the motor, and a plunger reacting between the carriage and motor to 25 lower the motor against the spring tension thereby to release the tension on the belt.

12. In a grinding machine, the combination of a carriage, a spindle quill carried thereby, a spindle rotatably mounted in the quill, a spindle pulley journalled in the carriage and in driving engagement with the spindle, a motor mounted for vertical movement, a motor pulley, a belt connecting the two pulleys, a spring engaging the 30 motor and urging the same upwardly against the 35 tension of the spindle pulley, means for varying the tension of the spring and an adjustable screw stop for limiting the upward movement of the motor, a plunger reacting between the carriage and motor to lower the motor against the spring 40 tension thereby to release the tension on the belt, and said plunger and adjustable stops mounted to be shifted into an inoperative position clear of the path of upward movement of the motor, thereby to permit the motor to be lifted off the 45 carriage.

13. In a grinding machine, the combination of a main column provided with a pair of vertically adjustable and relatively stationary stops, a tool supporting carriage mounted on the column for vertical movement, said carriage provided with a stop operable between the pair of stationary 50 stops to limit the vertical movement of the carriage in both directions and means for raising and lowering the carriage, and said carriage stop constituting a spring pressed plunger adapted to 55 be retracted into an inoperative position free of the stationary stops.

14. In a grinding machine, the combination of a grinding tool supporting carriage guided for 60 vertical movement, two means each operatively connected to the carriage to shift it vertically independently of the other, one of said means comprising a manually actuated lever for quick shifting into an approximately correct position and the other comprising a manually actuated micrometer lead screw for refined adjustment of the carriage into the desired correct position and control means for connecting and disconnecting said lead screw from the carriage at will and resisting 65 actuation by the lever when connecting the lead screw with the carriage and said lever permitting actuation of the carriage by the lead screw.

15. In a grinding machine, the combination of 70

- a main column, a carriage mounted thereon for vertical movement, a grinding tool mounted for rotary movement in the carriage, mechanism for shifting the carriage and with it the grinding tool 5 vertically on the column, said mechanism including a vertically extending lead screw mounted in the column, manually actuated means for rotating the lead screw, a two-part split nut mounted in the carriage and adapted to engage the lead screw whereby the rotation of the lead screw will shift the carriage vertically, means including a vertical slot in the carriage and a binding screw carried by the nut and extending through the slot for adjustably securing the split 10 nut to the carriage at any position along the length of the lead screw, and control means for moving the two parts of the split nut to and from their operative engagement with opposite sides of the lead screw.
- 15 16. In a grinding machine, the combination of a grinding tool, mounted for rotary movement about its axis and for shifting the tool vertically, a support for said tool, manually controlled mechanism for minutely shifting the support and 20 with it the grinding tool into a desired position, said mechanism including a vertically extending lead screw mounted for rotary movement and otherwise fixed relative to the support, a split nut for engaging the feed screw, a casing for the 25 split nut provided with means for securing the split nut to the tool support in vertically adjusted position relative to both the support and the lead screw and resilient means between the casing and split nut tending to maintain the nut in 30 engagement with the lead screw.
17. In a grinding machine, the combination of a grinding tool journalled for rotary movement about a horizontal axis, a flat plate constituting a vertically shiftable carriage for supporting the 35 same, a manually actuated lever for shifting the carriage vertically, a lead screw and split nut organization for shifting the carriage vertically, said organization including a casing, means for detachably securing the casing to the carriage at will, a two-part split nut slidably mounted in the casing, means tending to cause the two parts of the nut to engage the lead screw and control means for moving the split nut from its operative engagement with the lead screw.
- 40 18. In a grinding machine, the combination of a carriage mounted for vertical movement, a grinding spindle mounted for rotary movement in the carriage and provided with a driving pulley, a motor guided for vertical movement on the carriage and provided with a pulley, a belt forming a driving connection between the motor and spindle pulleys and a coiled spring located between the carriage and motor for resiliently supporting the motor from the carriage and means 45 for adjusting the tension on the spring thereby to regulate the tension on the belt.
- 45 19. In a grinding machine, the combination of a main column provided with a pair of vertically adjustable and relatively stationary stops, a tool supporting carriage mounted on the column for vertical movement, said carriage provided with a stop operable between the pair of stationary stops to limit the vertical movement of the carriage in both directions and the stop on the carriage including a spring pressed element disposed normally in line between the pair of stops on the column and said element adapted to be withdrawn from said path to permit the carriage to be moved independently of the stops.
- 50 20. In a grinding machine, the combination of a column provided with two pairs of vertically adjustable and relatively stationary stops, a tool supporting carriage mounted on the column for vertical movement, said carriage provided with two stops, one for each pair of stationary stops and each arranged for limiting the vertical movement of the carriage in both directions when located between its associated stationary stops and each carriage stop movable into an inoperative, out of the way position whereby either of the two sets of stops may be utilized at will to control the limits of permissible movement of the carriage.
- 55 21. In a grinding machine, the combination of a main column, a carriage slidably mounted on the column for vertical movement, a grinding tool journalled in the carriage for rotary movement about an axis fixed relative to the carriage, means including adjustable stops acting between the carriage and column for limiting the extent of and for locating the permissible location of travel of the carriage and thus of the tool axis, manually actuated means for quickly and roughly locating the carriage to bring the tool axis approximately into a desired position and manually 25 actuated micrometrical feed means acting on the carriage when so roughly located to bring the tool axis more accurately into the desired position.
- 60 22. In a grinding machine, the combination of a main column, a carriage slidably mounted thereon for vertical movement, a grinding tool journalled on the carriage for rotary movement, a channel plate carried by the column, a plurality of stops located on the channel plate, means for adjusting the stops relative to each other, means for locking the stops in their adjusted positions, a set screw carried by each stop, means for locking each set screw to its associated stop and a manually actuated retractable stop carried by the 40 carriage and disposed when in operable position between a pair of said set screws and disposed when in an inoperative position clear of the stops on the channel plate.
- 65 23. In a grinding machine, the combination of a main column, a carriage slidably mounted thereon for vertical movement, a grinding tool journalled for rotary movement on the carriage and movable vertically therewith, means for controlling the limits of movement of the grinding tool while operating in two zones of movement, said means comprising a channel plate carried by the column, four relatively stationary stops slidably mounted on the channel plate, one above the other, means for securing each stop to the 55 channel plate, each stop provided with a set screw and with the two upper and the two lower set screws facing each other to form two adjustable space defining means, the carriage provided with two retractable stops, one spaced above the other 60 and both adapted to operate in either of the spaces defined by the upper or lower pairs of relatively fixed stops whereby with one setting of the relatively fixed stops the carriage may be operated selectively in either a high or a low zone 65 of operation.
- 70 24. In a grinding machine, the combination of a carriage mounted for vertical movement, a grinding tool journalled for rotary movement on the carriage and movable vertically therewith, a motor for driving the tool provided with a base slidably mounted on the carriage for vertical movement, an adjustable stop between the carriage and motor base for locating the motor in a preset position on the carriage and means react- 75

ing between the motor base and carriage for forcing the motor into said position prefixed by the adjustment of the stops.

25. In a grinding machine, the combination of 5 a carriage mounted for vertical movement, a grinding tool journaled for rotary movement on the carriage and movable vertically therewith, a motor for driving the tool provided with

a base slidably mounted on the carriage for vertical movement and an adjustable stop between the carriage and motor base for locating the motor in a preset position on the carriage, said stop being movable into an inoperative position to permit the motor and its base to be slid off the carriage. 5

CARL J. HERTLEIN.
